PROTECTOR FOR FOODS

Thomas Tighe, Jr., Chicago, Ill.

Application August 25, 1932. Serial No. 630,452

3 Claims. (Cl. 65—53)

This invention relates to a protector for foods placed upon service plates, and has for its object to provide, in a manner as hereinafter set forth, a device of the class referred to for encompassing, in protecting relation, the food upon a plate when transporting the latter from a point of food supply to the point of service, with the protector so constructed to enable a plurality of protectors to maintain a series of service plates in stack relation with respect to each other to permit for conveniently and expeditiously transporting the stack by a single waiter for the purpose of serving quickly a number of persons at a banquet, and with the protectors acting to not only protect the foods upon the stacked plates but also preventing the foods from cooling while being transported to the point desired.

A further object of the invention is to provide, in a manner as hereinafter set forth, a protector for the purpose referred to including a body part having a reinforced rigid supporting means at an end thereof to increase the life of the protector.

Further objects of the invention are to provide, in a manner as hereinafter set forth, a protector for the purpose set forth, which is simple in its construction and arrangement, strong, durable, compact, thoroughly efficient in its use, conveniently handled and comparatively inexpensive to manufacture.

To the above ends essentially, and to others which may hereinafter appear, the invention consists of such parts, and such combination of parts which fall within the scope of the invention as claimed.

In the drawing:

Figure 1 is a perspective view of a food protector in accordance with this invention.

Figure 2 is a cross sectional view thereof.

Figure 3 is a fragmentary view in vertical section upon an enlarged scale.

Referring to Figures 1, 2 and 3 of the drawing, the food protector shown thereby comprises a body portion 1 in the form of an annulus or ring gradually decreasing in diameter from its bottom to its top whereby said body portion 1 is of tapered contour. The height of body portion 1 can be as desired and the lower terminal part 2 of the latter is directed upon an outwardly extending curve. The part 2 merges into an annular supporting flange 3 of angle-shaped cross section and formed of a horizontal leg 4, a depending vertical leg consisting of an inner portion 5, a lower rounded bend 6 and an outer portion 7 and a rounded upper bend 8 between leg 4 and the portion 5.

The top edge of portion 7 is flat and it is arranged in alignment with the point of emergence of the bend 8 with portion 5. The top edge of portion 5 is the outer terminus of the body of flange 3. The forward face of portion 5 is in snug abutting engagement throughout with the rear face of the portion 7. The bend 6 connects the portions 5, 7 together.

The cross sectional width of the horizontal leg is materially greater than the height of the vertical leg. The legs are disposed at right angles to each other. The leg 4 slightly inclines downwardly from part 2 to bend 8.

The top of body portion 1 is formed with an annular upper supporting flange 9 of angle-shaped cross section disposed inwardly and extending upwardly with respect to body portion 1. The flange 9 comprises a horizontal leg 10 which merges into the top of body portion 1 and extends inwardly at right angles to the latter. The leg 10 merges into an upwardly extending vertical leg formed of an inner portion 11, an upper rounded bend 12 and an outer portion 13. The vertical leg extends upwardly from the horizontal leg 10 and the latter is connected to portion 11 of the vertical leg by a lower rounded bend 14. The bottom edge of portion 13 is positioned in alignment with the point of emergence of the bend 14 with the portion 11 of the vertical leg. The bottom edge of portion 13 is spaced above the remaining part of bend 14 spaced above. The portions 11, 13 of the vertical leg of the upper flange are in snug contact throughout. The cross sectional length of the leg 10 is of greater length than the height of that vertical leg into which it merges.

When the protector is in position with respect to a service plate, the leg 5 seats upon the marginal portion of the upper face of such plate, and the depending vertical leg encompasses the edge of said disk to prevent the shifting of the protector relative to the disk. The body portion 1 encompasses the food upon the plate. When a service plate is stacked upon a protector mounted on a lower service plate, the bottom of the upper plate is seated upon the bend 12, and the flange, rib, bead or ridge on the lower face of the upper plate is encompassed by the inner portion 11 of the vertical leg of the upper supporting flange. This arrangement prevents the upper service plate from shifting relative to the protector which is mounted on the lower plate.

The protector is constructed of any suitable material, preferably sheet metal of the desired gauge.

What I claim is:—

1. In a food protector, a body portion of ring-like form provided at its bottom with an outwardly directed annular lower supporting flange of angle shape cross section to provide a horizontal and a vertical leg, the latter depending from the former and consisting of a pair of vertical portions snugly abutting throughout, one of said portions terminating in the other and having a free edge spaced below the upper face of said horizontal leg, the said other portion merging into said horizontal leg, said body portion provided at its top with an inwardly directed annular upper supporting flange of angle shape cross section to provide a horizontal leg and a vertical leg, the latter extending upwardly from the former and consisting of a pair of vertical portions snugly abutting throughout, one of said portions of the vertical leg of the upper flange merging into the other and having a free edge spaced above the upper face of the horizontal leg of the upper flange, the horizontal leg of the upper flange having its cross sectional length greater than the height of the vertical leg of the upper flange.
- 15 2. In a food protector, a body portion of ring-like form provided at its bottom with an outwardly directed annular lower supporting flange of angle shape cross section to provide a horizontal leg and a vertical leg, the latter extending upwardly from the former and consisting of a pair of vertical portions snugly abutting throughout, one of said portions of the vertical leg of the upper flange merging into the other and having a free edge spaced above the upper face of the horizontal leg of the upper flange.
- 20 3. In a food protector, a body portion of ring-like form provided at its bottom with an outwardly directed annular lower supporting flange therefor and at its top with an inwardly directed annular upper supporting flange for a dish adapted to be arranged in superimposed relation with respect to the protector, said upper flange being of angle-shape cross section to provide a horizontal leg and a vertical leg, the former extending inwardly from the top of said body portion and the vertical leg extending upwardly from the inner side of the horizontal leg, the said vertical leg consisting of a pair of vertical portions snugly abutting throughout, one of said portions of said vertical leg merging at its upper end into the upper end of and being of less height than the other portion of the vertical leg.

merging into said horizontal leg, said body portion provided at its top with an inwardly directed annular upper supporting flange of angle-shape cross section to provide a horizontal leg and a vertical leg, the latter extending upwardly from the former and consisting of a pair of vertical portions snugly abutting throughout, one of said portions of the vertical leg of the upper flange merging into the other and having a free edge spaced above the upper face of the horizontal leg of the upper flange, the horizontal leg of the upper flange having its cross sectional length greater than the height of the vertical leg of the upper flange.
